UNITED STATES PATENT OFFICE.

JACOB FELBEL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

1,053,374.

Specification of Letters Patent. Patented Feb. 18, 1913.

Application filed November 1, 1904. Serial No. 230,971.

To all whom it may concern:

Be it known that I, JACOB FELBEL, citizen of the United States, and resident of the borough of Manhattan, city of New York, in the county of New York and State of New York, have invented certain new and useful Improvements in Type-Writing Machines, of which the following is a specification.

10 This invention relates to improvements in typewriting machines which contain pivoted typebars. It is especially intended for use in front-strike machines. Its object is to improve the construction of the pivotal connections between the typebars and their hangers or supports, and the means for securing typebar hangers to their supporting segment.

15 The invention consists of the various features of construction, combinations and arrangements of parts, which will be herein-after fully described and particularly defined in the appended claims.

In the accompanying drawings in which 20 like reference numerals designate like parts in different views, Figure 1 is a front view of fragments of a typebar segment of a front-strike machine, and of typebar hangers attached to the segment, typebars 25 shown in cross-section being pivoted in the hangers; Fig. 2, a vertical cross-section of the segment and a side view of two hangers and typebars mounted thereon; Fig. 3, a longitudinal section, on an enlarged scale, of 30 a hanger with a typebar pivoted therein, the typebar and parts of the pivotal connection between it and the hanger being out on the axis of the pivotal connection; Fig. 4, an enlarged front view of a fragment of the 35 segment with hangers affixed to it; and Fig. 5 is a top view, partly broken away, of one of the type bars and its hanger.

Although this invention is applicable to typewriting machines of different styles, its 40 utility is greatest in front-strike machines containing typebars pivoted to segmentally arranged hangers. It lessens the tendency of pivoted typebars to work loose in consequence of wear on their bearings and of 45 insecurely fastened hangers. Especially in front-strike machines of the style above mentioned is this tendency troublesome. It so affects the typebars next to and near the ends of the segment that the alinement of 50 the writing is liable to be rendered imper-

fect before a machine has been long in use. The weight of a typebar which is next to one end of the segment, or between one end and the middle of the segment, subjects the pivotal bearings to wearing pressure at the 55 front of the bearing above the bar and at the back of the bearing below the bar. Hence as the bearings wear, the type of the bar sag so that they do not reach the true printing point when the typebar is actuated, 60 and whatever the wear may be it impairs the action of the typebar more than the same amount of wear impairs the action of a bar at the middle of the segment where the wear on the bearings of a bar is mainly on 65 one side only of its pivotal axis. The character of wear on the bearings of any bar is affected by the location of the bar. The farther a typebar is from the middle of the 70 segment the more the weight of the typebar causes the bearings to wear and the more 75 does slight wear of the bearings impair the action of the bar.

Typebar bearings such as form part of the 75 invention herein described are especially fit 80 for use in front-strike machines of the style mentioned above, because they largely, if not wholly, remedy the evils which result from unevenness and other differences in the 85 wear of the common pivotal typebar bearings, and which affect the alinement of the writing, the touch of the keys, and the operation of other parts of the mechanism.

The segment 1 shown herein has on its 90 front face two concentric projections 2 and 3, in which radial slots 4 are cut, the backs of 95 the slots being even with the flat surface 5 of the segment between the projections 2 and 3. The segment is to be supported in the frame 100 of a machine by suitable means and may be made movable up and down if desired to provide for upper and lower case writing.

Each of the typebar hangers has a thin 105 oblong stem 6, and a furcate head between whose cheeks 7 a typebar is secured. A 110 hanger may be a single piece of metal folded on itself, the parts forming the stem being riveted together with rivets 8, as appears by Fig. 3, or may be composed of two pieces riveted together, as shown in Fig. 4. There are hangers of two forms, those of one form having longer stems than those of the other, and the stem of each hanger has in it a bend or transverse corrugation 9. The long and short hangers alternate on 115

the segment, the stems of the long hangers extending between the heads of the short hangers, and the heads of the long hangers overlapping the upper edges of the short hangers. This arrangement renders the grouping of the hangers very compact. The stem of each hanger is confined in one of the slots 4 in the projections 2 and 3 and the hangers are secured to the segment by means of inner and outer sets of retaining screws 10 and 11, which are screwed into threaded holes in the segment between the slotted projections and near the inner and outer edges of the segment respectively. The screws of each set alternate in arrangement with the screws of the other set, and the stem of each hanger extends between a screw of the inner set and a screw of the outer set, and the heads of the screws overlap the stems of the hangers and hold them tightly in the slots. Any two adjacent hangers are thus secured in their slots by three screws, one of these screws being between the stems of the two hangers and overlapping them both with its head, and the stems of both hangers being between the two other screws, and the head of each of the latter screws overlapping the stem of one of the hangers. The curved or corrugated portions 9 of the stems of the hangers afford spaces in which the screws 10 fit between the stems. The rear edges of the stems of the hangers fit against the backs of the slots 4, the space between the projections 2 and 3 affording room for the corrugations 9. The heads of the retaining screws 10 and 11 may bear immediately on the front edges of the stems of the hangers, or washers or plates may be inserted between the heads of the screws and the hangers, as indicated in Fig. 4, in which, for example, plates 12 are shown, each plate encompassing screws 10 and 11 and bearing on the stems of three hangers. The hangers are very firmly secured to the segment by the means described, and any hanger may be easily applied to and removed from the segment.

The pivotal connection between each typebar 13 and its hanger is preferably composed of an axis 14 fixed in the typebar and of co-acting bearings attached to the hanger. But the invention may be applied to other forms of pivotal connections, such, for example, as those in which an axis is affixed to a hanger and bearings are mounted on a type bar, or in which bearings mounted on a typebar co-act with pins attached to a hanger. Tapering journals 15 are formed on the axis 14 at its ends, and these journals fit in tapering bearings supported by the head of the hanger. These bearings, like the jewel bearings of watches, may be the hardest precious stones which can be used, or others as crystals, garnets,

etc., or even glass of hard quality. The terms "jewel" and "jewel bearing" are used herein to designate generally such stones or substances, and bearings formed therein. The jewels 16 of each bearing are confined in cups or bezels 17 by suitable means, such as lips 18 formed on the bezels and bent inward over the edges of the jewels, the bezels being contained in holes in the cheeks 7 of the hanger. The bezels 75 may be permanently fixed in the hanger, or may be screwed into the cheeks of the hanger as shown, so as to enable them to be adjusted, and to be removed from the hanger. The bezels shown are provided with external screw threads 19 which engage with threads cut around the holes in the hanger, and in the base of each bezel are pin-holes 20 to enable the bezels to be turned with a spanner-wrench. 80

The combination of jewel bearings with the hangers and type bars of a typewriting machine is believed to be broadly new, and productive of results which have not hitherto been secured. It is to be understood, 90 therefore, that various changes of form may be made in the hangers, type bars, and bearings shown and described herein without departing from the substance of the invention.

What I claim as new and desire to secure by Letters Patent, is:—

1. In a typewriting machine, the combination of a segmental typebar support containing radial slots, a system of typebar hangers 100 having stems fitting in said slots, and inner and outer sets of retaining screws, the stem of each hanger extending between a screw of the inner set and a screw of the outer set, and said stem being secured in the slot by the 105 heads of these screws overlapping it.

2. In a typewriting machine, the combination of a segmental typebar-support containing radial slots, a system of typebar hangers 110 having stems fitting in said slots, and inner and outer sets of retaining screws, the screws of one set alternating in arrangement with the screws of the other set, and the stem of each hanger extending between a screw of the inner set and a screw of the outer set, and 115 said stem being secured in the slot by the heads of these screws overlapping it.

3. In a typewriting machine, the combination of a segmental typebar-support containing radial slots, a system of typebar hangers 120 having stems fitting in said slots, and inner and outer sets of retaining screws, any two adjacent hangers being secured in their slots by three screws, one of these screws being between the stems of the two hangers and overlapping both stems with its head, and the 125 stems of both hangers being between the two other screws, and the head of each of the latter screws overlapping the stem of one of the hangers.

4. In a typewriting machine, the combination of a segmental typebar support provided with concentric projections containing radial slots, a system of typebar hangers having stems fitting in said slots, the stems of the hangers being curved between said projections, and retaining screws whose heads overlap the stems of the hangers and secure them in the slots, two of said screws being arranged to act on each hanger.

5. In a typewriting machine, the combination of a segmental typebar support provided with concentric projections containing radial slots, a system of typebar hangers having stems fitting in said slots, the stems of the hangers being curved between said projections, and inner and outer sets of retaining screws whose heads overlap the stems of the hangers and secure them in the slots, two of said screws being arranged to act on each hanger.

6. In a typewriting machine, the combination of a segmental typebar support provided with concentric projections containing radial slots, a system of typebar hangers having stems fitting in said slots, the stems of the hangers being curved between said projections, and inner and outer sets of retaining screws, the stem of each hanger extending between a screw of the inner set and a screw of the outer set, and the heads of the screws overlapping the stems of the hangers and securing them in the slots, two of said screws being arranged to act on each hanger.

7. In a typewriting machine, the combination of a set of type bars that act on the front of the platen, a set of type bar hangers, and a set of connections common to the type bars and hangers and comprising metal pivots, and jewel bearing-blocks having recesses in which the pivots fit.

8. In a typewriting machine, the combination of a set of type bars that act on the front of the platen, a set of bifurcated type bar hangers, and a set of connections common to the type bars and hangers and comprising metal pivots, and jewel bearing-blocks having recesses in which the pivots

fit, the pivots being fast on the bars, and the jewels being attached to the branches of the 50 hangers.

9. In a typewriting machine, the combination of a set of type bars that act on the front of the platen, a set of bifurcated type bar hangers, and a set of connections common to the type bars and hangers and comprising metal pivots, and jewel bearing-blocks having recesses in which the pivots fit, the pivots being fast on the bars, and the jewels being confined in screw-threaded 55 bezels fitting in the branches of the hangers.

10. In a typewriting machine, the combination of a segmental typebar-support, a system of typebar hangers thereon, inner and outer sets of retaining screws, the screws of 65 one set alternating in arrangement with the screws of the other set, and plates confined between the heads of the screws and stems of the hangers, each plate encompassing a screw of each set and bearing on three 70 hangers.

11. In a typewriting machine, the combination of a type bar having a pivotal portion on each side thereof, and a forked type bar hanger having in each fork an adjustable support provided with a jewel bearing, the pivotal portions of the type bar and the bearings in the jewels being formed or constructed so as to properly support the type bar against endwise and sidewise pressures 75 80 during the vibratory movements of the type bar.

12. In a typewriting machine, the combination of type bars having pivots, bifurcated hangers having tapped arms, screw bezels inserted practically flush with the outsides of 85 said arms, and jewels supported by the bezels.

Signed in the borough of Manhattan, city of New York, in the county of New York 90 and State of New York, this 31st day of October, A. D. 1904.

JACOB FELBEL.
